DESIGN FOR AN INDUSTRIAL TRUCK

William W. MacDonald, Mountain View, and John R. Pomfret, San Francisco, Calif., assign-ors to Max L. Rosenfeld, San Francisco, Calif.

Application April 25, 1940, Serial No. 91,942

Term of patent 14 years

To all whom it may concern:

Be it known that we, William W. MacDonald and John R. Pomfret, citizens of the United States of America and residents, respectively, of Mountain View, county of Santa Clara, State of California, and of the city and county of San Francisco, State of California, have invented a new, original, and ornamental Design for an Industrial Truck, of which the following is a specification, reference being had to the accompanying drawing, forming part thereof.

The characteristic feature of our design resides in the portions shown in full lines in the drawing.

We claim:

The ornamental design for an industrial truck, as shown and described.

WILLIAM W. MACDONALD.
JOHN R. POMFRET.
